DESIGN FOR A CHILD'S TOY

Alice K. Carver, Pelham, N. Y., assignor to Richard G. Krueger Inc., New York, N. Y., a corporation of New York

Application February 14, 1945, Serial No. 117,929

Term of patent 14 years

(Cl. D34—4)

To all whom it may concern:

Be it known that I, Alice K. Carver, a citizen of the United States and a resident of Pelham, in the county of Westchester and State of New York, have invented a new, original, and ornamental Design for Child's Toy, of which the following is a specification, reference being had to the accompanying drawing, forming part thereof, in which—

Fig. 2 is an edge view thereof;

Fig. 3 is a rear view.

I claim:

The ornamental design for a child's toy, as shown.

ALICE K. CARVER.
